STOP MOTION MECHANISM

Michael Antonevich, New Brunswick, N. J., assignor to Crawford Manufacturing Company, Inc., New Brunswick, N. J., a corporation of New Jersey

Application April 8, 1948, Serial No. 19,841

18 Claims. (Cl. 66—163)

1

This invention relates to textile machinery and more particularly a device used on a knitting machine which tensions the yarn and at the same time automatically stops the knitting machine in the event that the desired tension in the yarn becomes too great or too small.

A standard stop motion or stop mechanism customarily employs a pivotally mounted finger over which the yarn passes as it is fed from the spools or bobbins to the needles. If for any reason the yarn becomes too taut, for example when a knot in the yarn is caught by the strainer, the tautness of the yarn depresses the stop motion finger, thereby closing an electrical circuit to a relay which in turn stops the main knitting machine motor. Furthermore, in the conventional stop motion device should the yarn break or become slack for some reason, the spring-loaded finger pivots upwardly to actuate the relay, likewise shutting down the knitting machine so that suitable adjustment can be made.

Patents disclosing devices of this general nature are: No. 1,816,765, A. Crawford; No. 2,178,982, M. Wachsman; No. 2,248,315, M. Wachsman; and No. 2,290,303, E. Vossen.

Two serious disadvantages have been found however, with stop motion mechanisms of the prior art. The first is due to the fact that these devices do not provide for supplementary tensioning for the finger under slightly increased conditions of yarn tautness. The second and more important disadvantage resides in the fact that the knitting of certain articles, such as stockings, requires some needles of the knitting machine to remain idle when the diameter of the stocking is decreased. Continued operation of the knitting machine then causes the idle spools or bobbins to rotate on their spindles and this in turn produces considerable slack in the idle yarn between the spools and the stop motion device. The stop mechanism over which the unused threads or yarn are run, thereupon shuts down the entire knitting machine even though a relatively slight amount of slack occurs for the above reason. This constant shutting down of the machine has been the cause of much lost time and is highly undesirable.

A primary object of the invention therefore, is to provide an improved stop motion mechanism for knitting machines which will not shut down the machine when slack occurs between the stop motion and the spool.

A further object of the invention is to provide in a stop motion device an adjustable tensioning finger which is spring-loaded over a portion of

2

finger travel and which is counterbalanced to provide a non-adjustable tension on the yarn throughout a further portion of finger travel.

A further object of the invention is to provide a supplementary tensioning finger or spring which resists excessive finger depression due to increased tautness in the yarn.

A still further object is to provide in a stop motion mechanism a single spring-loaded adjustable contact mechanism which closes an electrical circuit both when the control finger is depressed beyond a predetermined point, and when it is raised beyond a predetermined point.

Further objects will be apparent from the specification and drawings in which:

Fig. 1 is a perspective of a preferred form of stop motion mechanism constructed in accordance with the invention;

Fig. 20 is a fragmentary detail on a reduced scale showing the fingers in the position when slack occurs between the stop motion and the spool and corresponds to the position of the fingers in Figs. 6 and 7;

Fig. 21 is a perspective showing the detailed construction of the fingers, counterweights, and actuating pivots; and

Fig. 22 is a fragmentary detail as seen along 22-22 of Fig. 12 showing the top view of the finger pivoting structure.

The invention comprises essentially the provision in a stop motion device of a clamping finger operatively associated with a rigid arm in such a way that normal operating tension on the yarn or threads as it passes over the fingers of the stop motion pivots the clamping finger away from the rigid arm, but when tension is decreased to a predetermined value, the finger presses the yarn against the arm to prevent actuation of the stop motion mechanism. The clamping finger as well as the stop motion and/or tension fingers are pivotally interlocked so that when the stop motion finger is depressed, the other finger or fingers are automatically depressed. The preferred form of the invention has separate clamping and supplementary tensioning fingers which are so constructed that when the clamping finger is depressed, only the supplementary tensioning finger is depressed automatically and when the main tensioning finger is depressed, both the clamping and supplementary tensioning fingers are automatically depressed.

The invention includes a modified form in which the supplementary tensioning spring acts directly on the clamping finger.

Referring now more particularly to Fig. 1 of the drawings, the preferred form of the invention comprises a vertically positioned housing 25 having a removable cover 26 to which is attached a bracket 27 for supporting the entire stop motion device on a knitting machine. The inner wall 28 of housing 25 (Fig. 5) is elongated and bent at right angles to form a bracket 29 to which is bolted or otherwise attached a horizontal frame member 30. A pin or shaft 31 is rigidly supported in rear wall 28 of housing 25 so that the yarn contacting fingers 32, 33 and 34 are supported by, and journaled on, shaft 31. Both fingers 32 and 34 are provided with conventional ceramic caps 35 on which the thread or yarn 36 runs, and in addition, have integral counterbalances 37 and 38 and are axially spaced and journaled on shaft 31 by means of bushings 39 and 40. Likewise, clamping finger 33 with integral counterbalance 41 is mounted on shaft 31 through bushing 42. Finger 33 may be formed from a double loop of wire having straight sides extending at right angles to shaft 31. In the preferred embodiment, finger 33 is positioned between fingers 32 and 34 so that it is unnecessary to provide a ceramic cap for finger 33 because the caps 35 on fingers 32 and 34 serve to guide and

contact the yarn under normal operating conditions.

Referring now to Fig. 2, it will be seen that shaft 31 extends into housing 25 and journals a pivoting contact plate or member 43. Plate 43 is connected to, and at all times turns with, finger 32 by means of a connecting pin 44 extending through an arcuate slot 45 in rear wall 28. The hub 32a of finger 32 also carries an actuating pin 46 which extends parallel to shaft 31 and over the shank of finger 33 so that as finger 32 is depressed, finger 33 is likewise depressed when pin 46 contacts the shank of finger 33. A similar action between fingers 33 and 34 is achieved by means of pin 47 positioned in the hub 34a of finger 34 and extending at right angles to the fingers but underneath the shank of finger 33 so that as finger 33 is depressed, finger 34 is automatically depressed when the shank of finger 33 strikes pin 47. In this way it will be seen that finger 34 may be moved independently of the other two fingers, whereas when finger 33 is depressed, it carries with it only finger 34, but when finger 32 is depressed, both fingers 33 and 34 are likewise depressed.

Referring more particularly to the action and cooperation between fingers 33 and 34, it will be noted in Fig. 2 that the upward pivoting movement of finger 34 is controlled by means of an adjustable limit stop 50 secured to the horizontal member 30 by means of screw 51. Downward pivoting of finger 34 is controlled by means of a helical torque spring 52 (Fig. 5), one end of which is secured in a serrated thumb nut 53 rotatably mounted on shaft 54 which is in turn supported in a downwardly depending flange 55 on member 30. A friction latch comprising a leaf spring 56 retains any desired adjustment of nut 53 and is secured to member 30 by means of screws 57, 57. The other end of spring 52 is mounted in link 58 pivoted on shaft 54 at one end, and to cross-link 59 at the other. Link 59 is likewise pivoted to counterbalance 38 by means of pin 60 (Figs. 2 and 8) so that torque of spring 52 is transmitted to finger 34 through both links.

When finger 34 is in the raised position of Fig. 2 so that it abuts limit stop 50, and when clamping finger 33 is likewise in the fully raised position as shown in Figs. 6 and 7 so that it abuts the undersurface of backing member 61, a slight clearance is provided between actuating pin 47 in counterbalance 38 and the underside of the shank of finger 33 as shown in Fig. 7. This clearance permits limited pivoting of finger 33 controlled only by counterbalance 41. Furthermore, the weight of counterbalance 41 is just enough to clamp thread 36 between finger 33 and backing member 61 in the event that slack occurs between the spool and the stop motion device. In this condition, no tension is imparted to the thread by means of finger 34 since the stop 50 prevents further upward movement of finger 34.

The cooperation and action of stop motion finger 32 is such that when a knot or other obstruction occurs in thread 36, the increased tension in the thread depresses finger 32, and automatically fingers 33 and 34, until plate 43 pivots on pin 31 to the extent that corner 62 of plate 43 touches insulated electrical contact 63 as shown in Fig. 4. Contact 63 is supported from member 30 by means of binding post 64, nut 65 and insulating bushings and washers 66, 67 and 68. Binding post 64 is connected to a relay which controls the main knitting machine motor so that if finger 32 is sufficiently depressed, the machine will be

stopped until the necessary repairs or adjustments can be made. The additional electrical elements and their operation are well known in the knitting machine art, and it is therefore believed unnecessary to describe them in greater detail.

Tension spring 70 (Figs. 3 and 6) is mounted on pin 71 on plate 43 at one end, and to a sleeve or plate 72 at the other end. Tension in spring 70 may be varied by means of serrated knob 73 which is integral with screw 74 engaging internal threads in plate 72. Knob 73 is retained in any desired position by means of friction finger 75 secured to housing 25 by means of screws 76, 76. It will thus be apparent that main tension spring 70 controls the pivoting movement of finger 32 at all times and in all positions so that the adjustment of this spring supplies the proper tension to the yarn for normal running. However, if less than normal running tension occurs in the yarn, the finger will pivot upwardly due to the force of spring 70.

In the event that the spool, from which thread 36 is fed, be disconnected from the knitting machine as is often the case or should there be a slight slack in the threads between the spool and the stop motion, finger 32 will pivot upwardly on shaft 31 to approximately the position shown in Figs. 6 and 7. The decreased or limited slack condition in the yarn between the stop motion and the needle prevents further upward pivoting of finger 32 in accordance with the adjustment of spring 70. This controlled or limited upward pivoting of finger 32 permits the knitting machine to continue in operation without actuating the stop relay since plate 43 is so constructed that the opposite corner 77 does not strike contact 63 until additional upward pivoting has occurred.

This is an important feature of the invention because in stop motion devices heretofore used, if slack occurred anywhere in the yarn between the spool and the needle, the stop relay was actuated thereby preventing operation even though continued operation with only a limited number of spools was required. Since the thread 36 is still engaged in the inoperative needle and since the thread is also clamped between finger 33 and backing member 61 in accordance with the weight of counterbalance 41, the upward movement of stop finger 33 is thus controlled and retained within the arc bounded by respective contact positions of corners 62 and 77 of plate 43 with contact 63. However, should excessive slack occur between the stop motion and the needle, as would be the case if the thread breaks, there is no restraint for upward pivoting of finger 32 and the stop relay is actuated when corner 77 touches contact 63. The position of finger 32 under these conditions is shown in Fig. 11.

It will be apparent that the stop mechanism is operative to shut down the knitting machine in the event of a broken thread regardless of whether the break occurs between the stop motion and the needle as described above, or between the stop motion and the spool. In the event that the break occurs between the stop motion and the spool, the slack thus caused in the thread will immediately permit finger 34 to pivot upwardly until it abuts stop 50. Likewise, finger 33 will pivot upwardly due to counterbalance 41 and lightly clamp the thread against member 61. However, this "clamping" pressure is sufficient to permit only limited upward pivoting of finger 32 as shown in Fig. 6 and the thread continues to run through the stop mechanism

until the break passes finger 33. At this point there is no longer any restraint on finger 32 due to yarn tension so that the finger immediately springs to the position of Fig. 11, thus stopping the machine in order that necessary repairs can be made. It will be noted that in the position of Fig. 6, corner 77 does not close the electrical circuit to the relay so that the machine continues to operate.

10 In normal operation, finger 32 supplies the entire thread tension by means of spring 70 due to the fact that finger 34 is automatically restrained by stop 50. The slight friction of finger 33 on the thread may be disregarded for purposes of thread tension due to the fact that counterbalance 41 barely overcomes the weight of finger 33. However, if the thread becomes tighter than would be the case under normal operating conditions, all fingers are depressed which brings into play the opposing tension of spring 52. If the taut condition is cured, the fingers return to their normal operating position without shutting down the machine. However, if the tension in the thread is not relieved, the fingers will be depressed to approximately the position of Fig. 9 whereupon the thread either slips off of finger 32 or the knitting machine is stopped due to closing of the circuit by engagement of corner 62 of member 43 with contact 63 as shown in Fig. 4. Of course, if the thread does slip completely off of finger 32 before this engagement is made, spring 70 instantly pivots finger 32 upwardly to the position of Fig. 11 so that the machine is stopped in either case.

35 Referring now to Figs. 12-22, I have provided

a modified form of stop motion structure which enables the same results to be achieved as was done with the structure of Figs. 1-11, but instead of three fingers there are only two in this form.

40 The stop motion housing comprises a horizontal plate member 100, the edge of which is bent downwardly at right angles to form sides 101 and 102 to which are attached vertical housings 103 and 104. The entire assembly has a generally inverted U shape. Covers 105 and 106 are secured to the housings 103 and 104 respectively by means of suitable screws 107. The fingers 108 and 109 pivot on shaft 110 which is rigidly mounted in the rear walls 111 and 112 of housings 103 and 104 respectively (Fig. 22). Axial positioning of the fingers is achieved by means of a long bushing 113 between the finger hubs 108a and 109a and short bushings 114, 114 between the hubs and walls 111 and 112. Fingers 108 and 109 are provided with counterbalances 115 and 116 which serve to balance the weight of the fingers. The tops of the fingers curve downwardly in a longitudinal direction as shown in Figs. 15 and 16 and also are upwardly convex to present a smooth 55 running surface for thread 117.

60 Finger 108 is provided with a prong 118 to prevent thread 117 from running up on the finger, and the shank 108a of finger 108 has a laterally extending abutment 119 positioned to overlap a similar abutment 120 on the shank 109a of finger 109 (Fig. 22). The positioning of abutments 119 and 120 is such that finger 109 may be fully depressed without affecting finger 108, whereas depression of finger 108 automatically depresses finger 109. The fingers of Figs. 12 to 22 are formed of thin sheet metal which may be stamped to provide the desired shape. An abutment or rigid arm 121 having a lower arcuate edge of the same shape as finger 109 is secured to side 101 by means of screw 122 so that when finger

109 is raised to its maximum position, thread 117 is lightly clamped between the finger and arm 121 as shown in Figs. 18 and 20.

The portion of shaft 110 which extends into housing 103 is provided with a spacing bushing or collar 123 and journals a contact plate or member 124 similar to plate 43 of Figs. 3 and 6. Member 124 is spring-loaded by means of helical tension spring 125 connected thereto by pin 126. The other end of spring 125 is attached to an internally threaded nut 127 which may be raised and lowered in the bottom portion of housing 103 by means of serrated knob 128 and threaded screw 129 engaging nut 127 (Fig. 16). Actuation of plate 124 by means of finger 108 is provided through pin 130 rigidly connecting the counterbalance 115 of finger 108 and the plate through an arcuate slot 131 in wall 111. It will therefore, be apparent that the tension applied to finger 108 depends upon the adjustment of knob 128 in substantially the same manner as the structure of Fig. 6.

Referring now to the opposite housing 104 (Fig. 15) into which pin 110 likewise extends, a link 132 is journaled on pin 110 and spaced from wall 112 by means of bushing 133, Fig. 22. Link 132 is spring-loaded in the same manner as contact 124 by means of helical tension spring 134 supported on the link by pin 135 and connected to threaded nut 136 which is movable in housing 104 by means of thumb nut 137 and screw 138. Plate 132 is provided with a pin 139 extending through arcuate slot 140 in wall 112 of housing 104 in such a way that pin 139 is parallel to pin 110 and extends over the counterweight 116 on finger 109. The location and adjustment of pin 139 with respect to counterweight 116 and slot 140 is important and provides the proper tensioning of finger 109 under various operating conditions.

Referring now to Fig. 15, it will be seen that pin 139 abuts the left hand extremity 140a of slot 140. This removes all pressure of spring 134 from finger 109 and the location of the slot terminus 140a with respect to the bottom edge of arm 121 as well as the location of the point of contact between pin 139 and counterbalance 116 is such that slight free pivoting movement of the finger is provided before finger 109 contacts arm 121. This will be apparent by referring to Fig. 15 in which the finger 109 is shown in the position of maximum depression without extending spring 134. Any additional downward pivoting of finger 109 will be controlled by spring 134 through the pin 139 (Fig. 13), but upward pivoting from the position of Fig. 15 is controlled only by the counterbalance 116, the weight of which is sufficiently greater than the weight of finger 109 to provide the desired clamping pressure on the yarn.

In this way, when slack occurs in thread 117 between the stop motion and the spool, the thread is securely but lightly clamped between finger 109 and arm 121 by means of counterbalance 116 only.

Increased tension in the thread 117 depresses the fingers so that when the tension is sufficient to depress either finger below the position shown in Figs. 15 and 16, spring 134 automatically comes into play to resist further depression, thereby tending to return the fingers to normal operating position. However, it will be seen that the tension in spring 125 is transmitted to the thread 117 at all times when the thread is on finger 108 and this is sufficient to provide the

normal operating tension. The additional tension of spring 134 comes into play only when more than normal tautness in thread 117 occurs, and such additional tension is provided regardless of which finger may be depressed the most since further downward pivoting of finger 108 automatically pivots finger 109 by means of abutments 119 and 120.

The electrical stop motion construction of the modified form of Figs. 12 to 22 operates in a manner generally similar to that of Figs. 1-11 so that limited pivoting of finger 108 without closing the circuit is provided. In the event that slack occurs between the stop motion and the spool, thread 117 will be lightly clamped between finger 109 and arm 121. Since the thread remains in the needle of the knitting machine, finger 108 will pivot upwardly until the slack between the stop motion and the needle is taken up. In this position finger 108 will be slightly raised as shown in Fig. 20. The pivotal position of contact member 124 corresponding to the position of finger 108 in Fig. 20 is shown in Fig. 17, and in this position the circuit is still open. Further upward pivoting of finger 108 immediately causes the corner 141 of contact 124 to touch the insulated spring clip 142 thereby stopping the knitting machine. Clip 142 is secured to the top of housing 103 by means of plate 143, insulating washer 144, insulating bushing 145 and screw 146. A suitable binding post 147 is retained by screw 146 and is electrically connected to the main relay in the conventional manner.

In the event that thread 117 becomes excessively taut, fingers 108 and 109 pivot downwardly until they reach the position shown in Fig. 19. At this point contact member 124 is turning counterclockwise in Fig. 16 and corner 148 of member 124 will engage clip 142 to actuate the stop relay. Whether thread 117 slips completely off of finger 108 before corner 148 completes the circuit is relatively immaterial because if the thread does slip off finger 108, the finger immediately pivots upwardly to the position shown in Fig. 18, likewise actuating the stop relay by means of corner 141 on contact 124. These alternate circuit closing positions of plate 124 are shown by the fragmentary dotted lines in Fig. 16.

It will thus be apparent that I have provided an improved stop motion device which is capable of handling any possible thread condition occurring in the knitting machine.

When there is excessive tautness, increased tension in the fingers is automatically provided by means of a reserve or supplementary spring. In the event that the tension of the reserve spring is still insufficient, the fingers are further depressed in which case the stop relay is energized by means of the completed relay circuit actuated by the finger, or the thread slips off of the fingers which also insures actuation of the stop relay.

When slack occurs in the thread, the cause may be one of two conditions. First, the slackness may be due to a broken thread. Should the break occur between the stop motion and the needle, all resistance to the springs 70 or 125 is removed, thus permitting the stop finger to fly upwards and actuate the stop relay. In the event that the thread breaks between the stop motion and the spool, the relay will not be actuated until the break passes under the clamping finger and backing member, but as soon as this occurs, the stop finger immediately flies upward

since all resistance to the stop finger spring is thus removed. The second and most important feature of my construction resides in the fact that when only limited slack occurs in the thread, which slack may be caused by vibration in the knitting machine or the fact that certain spools are not used in performing part of the knitting operation, the stop finger is prevented from shutting off the machine due to the controlled clamping action of a second finger against a backing member in conjunction with limited pivoting of the stop finger without closing the circuit to the stop relay.

I claim:

1. A stop motion assembly for knitting machines comprising a housing, a plurality of fingers pivoted in said housing, and a rigid arm attached to the housing in registry with one of said fingers whereby a thread is pressed between said arm and one of said fingers when the finger pivots toward the arm.

2. A stop motion assembly in accordance with claim 1, in which one of said fingers actuates an electrical contact to close a relay circuit when the finger is in maximum raised and depressed positions and in which the relay circuit remains open when the finger is intermediate said maximum raised and depressed positions.

3. A stop motion assembly in accordance with claim 1, in which one of the fingers is spring-loaded throughout the entire pivoting movement of the finger, and means for adjusting the tension of said spring.

4. A stop motion assembly in accordance with claim 1, in which one of the fingers is spring-loaded during the lower portion of finger travel only, and an abutment for said finger to limit further upward pivoting.

5. A stop motion assembly in accordance with claim 1, in which one of the fingers serves as a main yarn tensioning finger and is provided with an adjustable tensioning spring for substantially the entire pivoting arc of the said finger, another of said fingers serves as a supplementary tensioning finger and is provided with a spring operable on said supplementary finger over the range of finger movement from normal operating position to a position of maximum finger depression, means for removing the spring action from said supplementary finger at a point below the position of normal operation, and a counterbalance for the finger for controlling further pivotal movement of the finger.

6. A stop motion assembly for knitting machines and the like, comprising an L-shaped housing having a horizontal portion and a vertical portion, a horizontal shaft rigidly attached to the vertical portion, a main tensioning finger pivotally mounted on said shaft, a counterbalance for said main tensioning finger, a clamping finger pivotally mounted on said shaft, a counterbalance for said clamping finger, a supplementary tensioning finger pivotally mounted on said shaft, a counterbalance for said supplementary tensioning finger, means for axially spacing the hubs of said fingers on the shaft, a stationary arm attached to the horizontal portion of the housing, a face on said arm adapted to register with the upper surface of the clamping finger, a contact plate pivotally mounted on the shaft in the vertical housing portion, a spring attached to said contact plate, means for adjusting said spring, a rigid connection between the contact plate and the main tensioning finger, a supplementary spring mounted in the horizontal housing portion, means for transmitting torque from said supplementary spring to the supplementary tensioning finger, means for adjusting said supplementary spring, and means for pivotally interlocking said fingers.

7. A stop motion assembly in accordance with claim 6 having an axial pin extending from the hub of the main tensioning finger over the shank of the clamping finger, an axially extending pin in the hub of the supplementary tensioning finger extending axially under the shank of the clamping finger, so constructed and arranged that when the main tensioning finger is depressed, both the clamping and supplementary tensioning fingers are automatically depressed and when the clamping finger is depressed only the supplementary tensioning finger is depressed and the clearance between the shank of the clamping finger and the axially extending member in the hub of the supplementary tensioning finger so that limited free pivoting between the arm and the clamping finger is controlled only by the clamping finger counterbalance is provided.

8. A stop motion assembly in accordance with claim 6 in which the contact plate in the vertical housing is flattened to provide limited pivoting of the main tensioning finger without closing the circuit to the relay.

9. A stop motion assembly for knitting machines and the like, comprising an L-shaped housing having a horizontal portion and a vertical portion, a horizontal shaft rigidly attached to the vertical portion, a main tensioning finger pivotally mounted on said shaft, a clamping finger pivotally mounted on said shaft, a counterbalance for said clamping finger, a supplementary tensioning finger pivotally mounted on said shaft, means for axially spacing the hubs of said fingers on the shaft, a stationary arm attached to the horizontal portion of the housing, a face on said arm adapted to register with the upper surface of the clamping finger, a contact plate pivotally mounted on the shaft in the vertical housing portion, a spring attached to said contact plate, means for adjusting said spring, a rigid connection between the contact plate and the main tensioning finger, a supplementary spring mounted in the horizontal housing portion, means for transmitting torque from said supplementary spring to the supplementary tensioning finger, means for adjusting said supplementary spring, and means for pivotally interlocking said fingers.

10. A stop motion assembly in accordance with claim 9 having a counterbalance for the main tensioning finger and a counterbalance for the supplementary tensioning finger.

11. A stop motion assembly in accordance with claim 9 in which the pivotally interlocking means comprise an abutment extending axially from the shank of one finger to overlap the shank of an adjacent finger whereby pivoting of the first finger is transmitted automatically to the second finger, and pivoting of the second finger occurs without affecting the first finger.

12. A stop motion assembly for knitting machines and the like comprising a U-shaped housing having a horizontal portion and a pair of vertical portions, a horizontal shaft rigidly supported between the vertical portions, a main tensioning finger pivotally mounted on said shaft, a supplementary tensioning finger pivotally mounted on said shaft, a stationary arm mounted

11

on the horizontal portion and in registry with the supplementary tensioning finger, a counterbalance for the supplementary tensioning finger, a supplementary spring in one of said vertical housings adapted to resist downward pivoting of said supplementary finger, means for connecting said spring to the shank of said supplementary finger, an abutment for said connecting means, said abutment being positioned to provide limited finger pivoting with said spring inoperative on the supplementary finger, a second spring adjustably mounted in the other vertical housing, and means for connecting said second spring to the shank of the first tensioning finger.

13. A stop motion assembly for knitting machines and the like comprising a U-shaped housing having a horizontal portion and a pair of vertical portions, a horizontal shaft rigidly supported between the vertical portions, a main tensioning finger pivotally mounted on said shaft, a supplementary tensioning finger pivotally mounted on said shaft, a stationary arm mounted on the horizontal portion and in registry with the supplementary tensioning finger, a counterbalance for the supplementary tensioning finger, a supplementary spring in one of said vertical housings adapted to resist downward pivoting of said supplementary finger, means for connecting said spring to the shank of said supplementary finger, an abutment for said connecting means, said abutment being positioned to provide limited finger pivoting with said spring inoperative on the supplementary finger, a second spring adjustably mounted in the other vertical housing, means for connecting said second spring to the shank of the first tensioning finger, and an electrical contact in said second vertical housing operable to close an electrical circuit upon maximum pivoting of the main tensioning finger.

14. A stop motion assembly in accordance with claim 13 in which the main tensioning finger is provided with a prong to limit longitudinal yarn movement thereover.

15. A stop motion assembly in accordance with

12

claim 13 in which the main tensioning finger is provided with an axial extension adapted to overlap the shank of the supplementary finger so that depression of the main finger automatically depresses the supplementary finger.

16. A stop motion assembly in accordance with claim 13 in which the abutment comprises an arcuate slot in the rear wall of the first vertical housing, a pin adapted to extend through said slot and overlap the shank of the supplementary finger, and a connecting plate pivotally mounted on said shaft, said connecting plate supporting the supplementary tension spring and the pin.

17. A stop motion assembly in accordance with claim 13 in which the fingers are formed of longitudinally concave and transversely convex metallic stampings.

18. A stop motion assembly in accordance with claim 13 having an electrical contact pivotally mounted in the second vertical portion, a connecting bar between said contact and the main tensioning finger whereby the contact and the main tensioning finger move as a unit, a stationary electrical contact mounted in said vertical portion, and a flat on the pivoting contact whereby an electrical circuit is closed when the finger is pivoted to maximum downward position and when the finger is pivoted to a maximum upward position but in which the circuit remains open during intermediate pivoting of the finger.

MICHAEL ANTOLEVICH.
